UNITED STATES PATENT OFFICE.

KNUT KLEVEN, OF MOUNT HOREB, WISCONSIN.

SILO-DOOR AND FASTENER.

No. 927,550.

Specification of Letters Patent.

Patented July 13, 1909.

Application filed January 20, 1909. Serial No. 473,302.

To all whom it may concern:

Be it known that I, KNUT KLEVEN, a citizen of the United States, residing at Mount Horeb, in the county of Dane and State of Wisconsin, have invented a new and useful Silo-Door and Fastener, of which the following is a specification.

This invention relates to silos and more particularly to improved means for locking the several door sections of the silo in closed position.

The object of the invention is to provide a silo having a continuous door opening and provided with a plurality of removable door sections forming a closure for said opening, there being a transverse bar secured to the exterior face of each door section and co-acting with pivoted members on the door frame for locking the door sections in closed position.

A further object is to provide means for clamping the transverse bars of the door sections in engagement with the pivoted members after the latter have been swung downwardly at the rear of said transverse bars.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification:—Figure 1 is a plan view of a portion of a silo constructed in accordance with my invention. Fig. 2 is a vertical sectional view of the same. Fig. 3 is a transverse sectional view taken on the line 3—3 of Fig. 1. Fig. 4 is a detail perspective view of one of the fastening devices detached.

Similar numerals of reference indicate corresponding parts in all of the figures of the drawings.

The improved silo forming the subject matter of the present invention includes a substantially cylindrical body portion 5, preferably formed of tongue and groove staves, and having its exterior walls reinforced and strengthened by the provision of a plurality of circumferential hoops 6. Two

or more of the staves on one side of the silo 55 are removed to produce a door-opening, preferably extending the entire height of the silo, and in which is seated a door frame 7 having its longitudinal bars spaced apart by transverse beams 8.

Interposed between the beams 8 are removable door-sections 9, the opposite ends of which fit within the rabbeted edges 10 of the adjacent transverse beams 8 and bear against shoulders 11, thereby to form abutments for the door sections and prevent the latter from being forced outward by the weight of pressure of the fodder or other material within the silo.

The doors 9 may be constructed in any 70 suitable manner but it is preferred to form the same of a plurality of superposed transverse strips connected by spaced vertically disposed cleats 12, the latter being rigidly combined with the body of the door by bolts 75 or similar fastening devices 13. The outer longitudinal edges of the cleats are preferably inclined or beveled in opposite directions from a central flat portion 14, and bearing against the flat portions of the cleats 12 of 80 each door is a transverse bar 15, the opposite ends of which are bent inwardly to produce angularly disposed fingers 16.

Pivottally mounted at 17 on the longitudinal bars of the door frame at the opposite 85 ends of the transverse bars 15 are locking members or latches 18 adapted to be swung downwardly to operative position at the rear of, and in engagement with the fingers 16 of the bars 15 so as to prevent the door sections 90 from dropping downward within the silo.

As a means for positively clamping the transverse bars 15 in engagement with the adjacent locking members 18, there are provided transverse bolts 19 which extend 95 through the body of the door and the adjacent longitudinal cleats 12 with their terminals 20 projecting through the flat bearing surfaces 14 for engagement with suitable clamping nuts 21, the latter being provided 100 with terminal finger pieces 22 so that the nuts may be rotated, thereby to bear against the exterior face of the bars 15 and thus force the fingers 16 of said bars laterally against the pivoted locking members 18. It will 105 here be noted that the downward swinging movement of the locking members 18 is limited by engagement with suitable stop

pins or studs 23 carried by the longitudinal bars of the door frame, whereby when the locking members are moved to operative position, the same will be supported in horizontal alinement with the adjacent transverse bars 15. It will also be noted that by spacing the transverse bars 15 from the exterior face of the door-sections, said transverse bars form in effect the rounds of a ladder so that an attendant may readily ascend or descend the silo. Thus it will be seen that by rotating the finger pieces 22 in one direction, the terminals 16 of the locking bars may be disengaged from the pivoted members 18 so as to permit the latter to be swung laterally to inoperative position, and in which position the door sections may be readily removed.

In order to replace the door sections it is merely necessary to position the same within the silo with the upper and lower edges thereof bearing against the shoulders 11 of the adjacent transverse bars 8 and with the opposite longitudinal edges of the door sections bearing against the inner face of the door frame 7 after which the pivoted locking members 18 are swung downwardly at the rear of the angular extensions 16 of the transverse bars and the finger pieces 22 of the clamping nuts adjusted to securely clamp the several parts together, in the manner before described.

Having thus described the invention what is claimed is:

35 1. A silo including a body portion having a door opening, a plurality of removable door sections forming a closure for said opening, a transverse bar secured to the exterior face of each door section, and locking members pivotally mounted on the body portion and movable laterally into engagement with the adjacent transverse bars.

45 2. A silo including a body portion having a door opening, a plurality of removable door sections forming a closure for said opening, a transverse bar secured to each section and provided with angular extensions, and locking members pivotally mounted on the body portion and movable to operative position in engagement with the angular extensions of the adjacent transverse bars.

55 3. A silo including a body portion having a door opening, a plurality of removable door sections forming a closure for the door opening, a transverse bar secured to each door section, locking members pivotally mounted on the body portion and movable to operative position in engagement with the adjacent transverse bars, and clamping devices passing through the door sections and the transverse bars for locking said bars in engagement with the pivoted members.

60 4. A silo including a body portion having a door opening, a frame seated in said door opening, a plurality of removable door sec-

tions forming a closure for said door opening, cleats secured to the exterior faces of the door sections, a transverse bar connecting the cleats of each door section, locking members pivotally mounted on the door frame and movable to operative position at the rear of the adjacent transverse bars, and means for locking the transverse bars in engagement with the adjacent pivoted members.

75 5. A silo including a body portion having a door opening, a door-frame seated in said opening, a plurality of removable door sections forming a closure for the door-opening, spaced vertical cleats secured to the exterior 80 face of each door section, a transverse bar connecting the vertical cleats of each door section and having their opposite ends provided with angular extensions, locking members pivotally mounted on the door-frame 85 and movable to operative position in engagement with the angular extensions of the adjacent transverse bars, and fastening devices piercing the doors and adjacent transverse bars for locking the latter in engagement with the pivoted members.

90 6. A silo including a body portion having a door-receiving opening, a door frame seated in said opening, a plurality of removable door sections forming a closure for said door-opening, spaced vertical cleats secured to the exterior face of each door-section and each having a central flat portion and oppositely inclined terminals, a transverse bar secured to the intermediate flat portions of the cleats of each door section and provided with oppositely disposed angular terminals, locking plates pivotally mounted on the door frame and adapted to be swung laterally to operative position in engagement with the terminals of the angular extensions, means for limiting the pivotal movement of the locking members, and fastening devices extending through the doors and engaging the adjacent transverse bars for locking the latter in contact with the pivoted plates.

95 7. A silo including a body portion having a door-receiving opening, a door-frame seated in said opening and provided with spaced transverse beams having their inner faces 100 rabbed to form stop shoulders, a plurality of movable door-sections forming a closure for the door-opening and having their opposite ends bearing against the adjacent shoulders of the transverse beams, spaced vertical cleats secured to the exterior face of each door section, transverse bars connecting said cleats and spaced from the exterior face of the door-sections to form the rounds of a ladder, the opposite ends of the transverse 105 bars being bent inwardly to form angular extensions, locking plates pivotally mounted on the door frame and movable downwardly to operative position at the rear of the angular extensions of the transverse 110 bars.

bars, pins disposed beneath the pivoted plates for limiting the downward movement thereof, threaded bolts extending through the door sections and the adjacent transverse bars, and nuts engaging the threads on the bolts for clamping the angular extensions of the transverse bars in engagement with the adjacent pivoted plates.

In testimony that I claim the foregoing as my own, I have hereto affixed my signature 10 in the presence of two witnesses.

KNUT KLEVEN.
